CLAIM

The ornamental design for a rubber crawler, as shown and described.

DESCRIPTION

FIG. 1 is a front perspective view of a rubber crawler showing our new design.

FIG. 2 is a front elevation view thereof.

FIG. 3 is a rear elevation view thereof.

FIG. 4 is a top plan view thereof.

FIG. 5 is a bottom plan view thereof.

FIG. 6 is a left side elevation view thereof; and,

FIG. 7 is a right side elevation view thereof.

The broken lines shown in the drawings are for the purpose of showing environmental structure only and form no part of the claimed design.
